RECEPTACLE FOR TOILET ARTICLES OR THE LIKE

Rose Boutwell, Denver, Colo.

Application July 15, 1954, Serial No. 31,449

Term of patent 14 years

(Cl. D86—10)

Fig. 1

To all whom it may concern:

Be it known that I, Rose Boutwell, a citizen of the United States, residing at Denver, county of Denver, State of Colorado, have invented a new, original, and ornamental Design for Receptacle for Toilet Articles or the like, of which the following is a specification, reference being had to the accompanying drawing, forming part thereof and in which:

Fig. 1 is a perspective view of a receptacle for toilet articles or the like embodying the design of my invention;

Fig. 2 is a top plan view of the receptacle of Fig. 1; and

Fig. 3 is an end elevation of the receptacle of Fig. 1.

I claim:

The ornamental design for a receptacle for toilet articles or the like, as shown.
